UNITED STATES PATENT OFFICE.

JESSE G. VINCENT, OF DETROIT, MICHIGAN, ASSIGNOR TO BURROUGHS ADDING MACHINE COMPANY, OF DETROIT, MICHIGAN, A CORPORATION OF MICHIGAN.

ADDING-MACHINE.

1,323,505.

Specification of Letters Patent.

Patented Dec. 2, 1919.

Application filed November 22, 1906. Serial No. 344,594.

To all whom it may concern:

Be it known that I, JESSE G. VINCENT, a citizen of the United States, residing at Detroit, in the county of Wayne and State 5 of Michigan, have invented certain new and useful Improvements in Adding-Machines, of which the following is a specification.

One object of the present invention is to equip an adding and listing machine with 10 an improved form of item counter which can be variously adjusted for the purpose of predetermining the number of itemizing operations to be performed by the machine in any series, the arrangement being such that 15 upon the completion of the series no further itemizing can be done until the counter is re-set. Thus the operator will be prevented from inadvertently over-running the previously estimated number of items for making 20 up a column. A further object of the invention is to provide for automatically resetting the item counter as an accompaniment to the taking of a total. A still further object of the invention is to provide for 25 eliminating the locking function at will so that whenever desired items can be indefinitely counted.

With these and incidental objects in view the invention consists in certain novel features of construction and combinations of 30 parts the essential elements whereof are recited in the appended claims and a preferred form of embodiment of which is illustrated in detail in the accompanying drawings and fully described hereinafter.

Of said drawings Figure 1 represents in left side elevation an adding and listing machine of the well-known Burroughs type, the casing and certain cross-shafts and studs 35 appearing in section as well as the carriage attachment at the rear and portions of the item counting and automatic locking mechanism of the present invention which is shown applied to said machine; Fig. 2 represents the item counting and automatic locking mechanism on an enlarged scale in left side elevation together with portions of the adding machine frame; Fig. 3 shows a portion of the machine key-board in left 40 side elevation with some parts broken away and in section, also parts of the total setting devices of the machine together with parts of the automatic locking mechanism taken on a vertical section inwardly beyond 45 the item counter index devices; Fig. 4 rep-

resents the item counter indexing devices in top plan view together with a fragment of the machine frame; Fig. 5 represents a development of the item counter index scales; Fig. 6 represents the itemizing and 50 automatic locking mechanism in right side elevation with a portion of the machine frame beyond and certain cross-shafts in section, as also a certain locking lug; Fig. 7 represents a vertical section taken through 55 the item counting and automatic locking mechanism transversely of the machine; and Figs. 8 to 12 represent different parts of the item counting and automatic locking mechanism detached in perspective. 60

The invention is illustrated in the present case as adapted and applied to the well-known Burroughs adding and listing machine for the details of which reference may be had to the William S. Burroughs Patents 70 Nos. 504,963 and 505,078 of June 12, 1893, but it is to be understood that the invention is not necessarily limited to this particular adaptation but may be applied to other types of adding and listing machines. The 75 machine as here shown employs the usual columns of depressible amount keys 291 which operate through bell crank levers 217 to thrust rearwardly the slotted strips or plates 214, the latter adapted to be caught 80 and held rearward by the engagement therewith of spring-actuated detent pawls 228 in the usual manner. The reference numeral 202 designates the usual round bar which 85 operates to disengage said detent pawls 90 from the strips and thrust the latter forward, this bar forming part of a bail comprising end arms 219 secured to a rock-shaft 207. This bail is as usual drawn rearwardly 95 by a coiled spring 1881 and arranged to be rocked forward against the stress of said spring and then released to be restored to rearward position, in each operation of the machine toward the close thereof. By the 100 present invention it is proposed to automatically lock this bail in its forward position when a predetermined number of items have been recorded and registered by the machine. To this end one of the arms 219 of the key-releasing bail has a depending portion 219^a carrying an outwardly projecting square lug 1859. This lug is adapted to be 105 engaged by a similarly formed notch 1859^a in the upper edge of the horizontally and forwardly extending arm 1813 of a bell 110

2

crank lever pivoted upon a frame stud 1850 and having a depending arm 1813^a. It will be seen that the locking of the bail in its forward position locks the entire key-board 5 so far as the amount keys are concerned because of preventing any rearward movement of the detent strips 214. This locked relation of parts is illustrated in Fig. 3 by full lines. This figure of the drawings also 10 illustrates the operation of unlocking the amount keys by the action of depressing the total key 295. The latter is of the familiar Burroughs type, being part of a bell crank lever 227 whose depending arm is coupled 15 through slot-and-pin connection with a link 226 which is in turn jointed to the lower end of an arm 227^a hung from a cross-shaft 200. In the present instance an additional link 1810 is jointed to the lower end of said 20 arm 227^a and is slotted at its rear end to embrace a stud upon the bell crank arm 1813^a. Through these connections it will be seen that depression of the total key will result 25 in swinging said bell crank arm rearwardly and correspondingly depressing the horizontally extending arm 1813 and disengaging it from the lug 1859 whereupon the spring 1881 will draw the detent-controlling bail rearwardly. The depression of the bell 30 crank arm 1913 is against the stress of a spring 1880 which tends to press an upturned extension 1813^b of the said arm 1813 into engagement with the periphery of a disk 1822, said extension being formed at its 35 upper extremity with a laterally turned foot 1813^c adapted to ride upon the periphery of said disk and to enter a notch 1822^a therein when the locking operation takes place. One side of said notch is abrupt but the opposite side is inclined so that by manipulation 40 of the disk the foot can be cammed out of engagement with the notch and the lever thus displaced so as to unlock the bail independently of the total key connections if desired, the slot in the rear end of the link 1810 providing for this as well as for the locking movement of the lever independently of said link. 45

The notched disk above mentioned is the medium through which the automatic locking of the key-board can be timed to take place at the conclusion of recording and registering a certain number of items as predetermined by the operator. To this end the disk is arranged to be turned and set at various positions and then returned step by step until the notch arrives opposite the end of the bell crank extension 1813^b. Said disk is secured to the inner reduced end of a stud 55 1831 (Fig. 7) journaled in a short sleeve 1830, the latter being in turn journaled in the heads 1834 and 1835 of a spring barrel 1836 which occupies a circular recess or aperture in the supporting frame-work of 60 the machine and is securely held in place by a screw 1836^a. Said stud and sleeve are shouldered to insure their proper longitudinal relation and the stud is formed on its outer end with a pair of lugs 1831^a (Fig. 9) to engage notches 1832^a (Fig. 12) in the 65 inner end of a relatively long sleeve 1832 which extends through the left-hand side of the machine casing (Fig. 7) and projects considerably beyond the same. This longer sleeve lies at its inner end within the outer portion of the shorter sleeve 1830 and at its outer end is longitudinally slotted in one side as shown at 1832 to receive a key 1892 carried by a knob 1833 surrounding the outer portion of said longer sleeve. It will 70 now be seen that by turning said knob the notched disk can be turned through the medium of the sleeves 1831 and 1832 and the engagement of the key 1892 with the slot of the latter. The knob 1833 has compounded with it a disk 1833^a formed with a peripheral flange 1837 marked off into graduations and inscribed with numerals as shown in Figs. 4 and 5 constituting an item scale by which to set the notched disk. A pointer 1890 fixed to a boss on the machine frame serves to indicate the zero position of the notched disk and to guide the operator in setting said disk by turning the knob 1833 from left to right. 75

The inner edge of the flange 1837 is formed with saw-teeth 1837^a for interlocking with similar teeth 1838^a upon the peripheral flange 1833 of a disk 1839 having a tubular boss 1839^a loosely embracing the 80 sleeve 1832 behind a flange 1832^a thereof. The peripheral flange 1833 is marked off into graduations the same as the peripheral flange 1837 and is likewise inscribed with numerals to constitute with said graduations an item scale but the numerals run in the opposite direction to those upon said flange 1837 as this latter scale is used to count the operations of the machine while the zero point of the first-described scale is being 85 moved back step by step. 90

The connections for turning the flanged disk 1839 step by step are of the following description: The tubular boss 1839^a of said disk is formed on its inner end with a pair of lugs 1839^b (Fig. 8) which fit notches 1830^a (Fig. 10) in the outer end of the sleeve 1830. There is secured upon the inner end of said sleeve a gear wheel 1821 which meshes with a smaller gear wheel 1820 journaled upon the shaft 207 and compounded through the medium of a suitable hub with a ratchet wheel 1819. The latter is arranged to be engaged and turned one 100 step in each operation of the machine by a pawl 1815 pivoted upon a stud 1860 (Fig. 2) which pivotally unites a vertical bar 1811 and an arm 1814 pivoted upon the stud 1850. A spring 1882 connects said arm with the tail of the pawl holding the latter yield- 105

110

115

120

125

130

ingly against a stud 1858 on said arm, the pawl being normally withdrawn from engagement with the ratchet wheel but ready to engage and turn the same when the bar 5 1811 is thrust upwardly. This bar is pivotally connected at its lower end through the medium of a stud 1855 with the rear arm of a lever 1812 pivoted upon a stud 1854 carried by the frame-work of the machine and 10 said lever is forked at its forward end to embrace a roller stud 1899 upon an arm of the familiar Burroughs lever 813, see Fig. 1. It will be seen that the oscillations of 15 said lever 813 will result in reciprocating the pawl through the connections described so that in each operation of the machine the ratchet wheel will be turned one step. It will further be seen that this intermittent 20 turning of the ratchet wheel will convey movement through the gearing described to the flanged item counting disk 1839 so that the scale on the latter will be moved past the pointer 1890, which will therefore denote on said scale the number of operations 25 which the machine has performed in any given series. At the same time the flanged disk 1833^a will be turned step by step by reason of the interlocking of the saw-teeth as hereinbefore mentioned so that the 30 notched disk 1822 will be moved until its notch comes opposite the bell crank locking lever extension 1813^b and the locking of the key-board takes place in the manner already described. It will be understood, however, 35 that the mere arrival of this notch opposite said extension will not be immediately followed by the locking of the key-board but that forward swing of the detent-controlling bail must ensue before the locking lever 40 can move upward and engage its notch with the lug 1859 of said bail, see Fig. 6.

It has been before stated that the knob 1833 and the sleeve 1832 are connected through the medium of a key 1892 and a 45 slot 1832^b. This is for the purpose of permitting the flanged disk 1833^a to be drawn outwardly and its saw-teeth disengaged from those of the flanged disk 1839. When this has been done the first-mentioned disk 50 can of course be rotated independently of the other disk. Thus in order to set the parts for locking the key-board after a predetermined number of operations of the machine the operator simply pulls the knob 55 1833 outwardly and then turns it to the right until the proper graduation comes opposite the pointer 1890 when the knob is released. The two disks are drawn into engagement by a spring 1885 contained within a recess 60 of the knob 1833 and surrounding the enlarged portion of a bolt 1857 which extends through the sleeve 1832, being shouldered to bear against the outer end thereof. The slotted head of this bolt overlies the spring 65 1885, the latter bearing at the opposite end

against the base of the recess in the knob. The reduced and screw-threaded inner end of said bolt engages a tapped bore of the stud 1831, see Fig. 7. It will be seen that the construction of parts just described provides for the spring 1885 constantly exerting itself to enforce engagement between the two flanged disks. 70

It has been stated that one of the objects of the present invention is to provide for re-setting the item counter automatically and to this end a coiled spring 1886 is placed within the barrel 1836 and secured at its inner end to the sleeve 1830. The outer end of the spring is preferably not rigidly connected with the barrel but frictionally engaged therewith so as to simply secure an average tension sufficient to turn the counter through one backward revolution. This prevents continued winding of the spring when the 75 counter makes more than one complete forward rotation, the spring slipping to prevent excessive winding. Of course it will be understood that the step-by-step turning of the notched disk is against the tension of 80 this spring 1886. To prevent retrograde movement of the ratchet wheel when the actuating pawl withdraws a restraining pawl 1816 is employed, the same being pivotally mounted upon a cross-rod or shaft 202^b 85 and held against the ratchet wheel by a spring 1883 connecting its tail with the frame of the machine, see Fig. 6. In order to bring about the re-setting of the counter by its motor spring 1886 it is of course necessary to displace this restraining pawl in addition to disengaging the locking lever from the notched disk. To this end the swinging arm 227^a of the total setting devices is 90 formed with a rearwardly projecting inclined finger 1816 which is arranged to act against the under-edge of the tail of the pawl 1816 when said swinging arm is moved rearwardly by depression of the total key. It 95 is desirable to provide for definitely stopping the counter when re-set by its motor spring so as to insure a fixed starting point and to this end a disk 1818 is employed, the same having the peripheral contour of a snail-cam. Said disk embraces the sleeve 100 1830 as shown in Fig. 7 and is formed with lugs to occupy notches 1818^a in said sleeve (Fig. 10) so as to turn therewith and hence with the flanged index disk 1839. A stop-arm 1817 is pivoted on a stud 1856 carried 105 by the frame of the machine and this arm is drawn against the periphery of the disk 1818 by a spring 1884. So long as operations of the machine are being counted said arm simply rides upon the periphery of the 110 disk dropping past the shoulder thereof as each complete rotation is made but it will be seen that this arm always stands ready to stop the counter at the same point when it is 115 re-set by the spring 1886, by presenting its 120 125 130

end to the abrupt shoulder of the disk as shown in Figs. 1 and 6.

When it is not desired to place a definite limit to the number of items in a series but at the same time to keep count of the items it is only necessary to keep the flanged disk 1833^a out of engagement with the flanged disk 1839. To facilitate this adjustment the same plate 1891 of which the pointer 1890 forms a part is provided with an outwardly projecting arm 1893 notched in its end to receive a stud 1894 which projects from the peripheral flange 1837 of the disk 1833^a, see Fig. 4. The arm 1893 projects sufficiently to hold the toothed flanges of the counter disengaged so long as the stud 1894 is against the notched end of said arm. This adjustment can be readily brought about by simply pulling the knob 1833 outwardly and turning it slightly to the left and then releasing it.

The operation of the invention will be more or less apparent from what has already been stated. With the parts standing at normal, that is with the zero marks of the two scales registering as shown in Fig. 4, should the operator desire to set the machine for a certain number of items he simply draws out the knob 1833 and rotates it to the right until the mark on the outer scale indicating the desired number of items comes opposite the pointer 1890 and then releases the knob whereupon the flanges of the two index disks become interlocked. Then as one item after another is recorded and registered in the machine the counter is turned step by step carrying the zero mark of the outer scale back toward the pointer and advancing the inner scale past said pointer to show the count. When the predetermined number of operations have been performed the notched disk will have been brought to position for receiving in its notch the end of the locking lever extension. Then when the detent-controlling bail is rocked forward its lug 1859 is carried over the notch of said locking lever and the latter rises and the bail is locked. The knob can then be again drawn out and turned to the left to carry the locking lever out of the notch whereupon the bail will be drawn back to its normal position by the spring 1881 and the key-board unlocked; then the knob can be turned to the right to set the lock for taking effect after the same number of operations of the machine as before or for a different number, while count of the total number of both series of operations is preserved on the inner scale. However, as in most cases either a grand total or a sub-total would be struck upon the conclusion of the listing of the predetermined number of items constituting a series, the above manipulation of the knob would not ordinarily be pursued. As before explained, the mere depression of the total

key has the effect of withdrawing the locking lever from the notch of the disk 1822 and disengaging said lever from the lug of the detent bail and also displacing the restraining pawl. This results in the two flanged index disks being turned back together by the spring 1886 so that the counter is automatically re-set for a repetition of the same number of itemizing operations. It will be noted in this connection that the key-board can be caused to become automatically locked after a number of itemizing operations in excess of those provided for by the scales shown in the present instance. For example, if it is desired to lock the key-board after 150 items have been recorded the operator will set the counter to lock after the seventy-fifth item has been recorded and registered and then upon the key-board becoming locked will simply press the total key and continue putting in items until seventy-five more have been recorded and registered. Thus upon the introduction of the 150th item the key-board will become locked.

It will now be seen that the above described construction is well calculated to thoroughly fulfil the objects primarily stated. At the same time it will be understood that this construction is susceptible of considerable modification within the scope of the invention.

What is claimed is:

1. In a machine of the character described, the combination of accounting elements, setting-up devices, actuating means, and means controlled by the latter and independent of the accounting elements and serving after a predetermined number of operations of said actuating means to prevent further use of the setting-up devices.

2. In a machine of the character described, the combination of accounting elements, manipulative amount-determining devices, a prime mover and connections for actuating the accounting elements, and means operated by said prime mover and independent of the actuating elements to prevent manipulation of the amount-determining devices after a predetermined number of operations of the prime mover.

3. In a machine of the character described, the combination of accounting elements, depressible keys for regulating movements thereof, means for locking said keys against depression, adjustable devices controlling said locking means, a prime mover, and connections therefrom for intermittently operating said adjustable devices and thereby effecting a locking of the keys after a predetermined number of operations of the prime mover.

4. In a machine of the character described, the combination with itemizing mechanism, of a notched disk, an index compounded

therewith and settable with the disk to varying positions measured by the number of items to be recorded or registered, means for moving said disk and index step-by-step, and a lock coöperating with the notched disk to automatically prevent further operations of the itemizing mechanism after reaching the number predetermined by the setting of the index.

10 5. In a machine of the character described, the combination with itemizing and totalizing mechanism, of a notched disk, an index compounded therewith and settable with the disk to varying positions measured by the number of items to be recorded or registered, means for moving said disk, and index step-by-step, and a lock coöperating with the notched disk to automatically prevent further operations of the itemizing mechanism after reaching the number predetermined by the setting of the index.

15 6. In a machine of the character described, the combination with accounting mechanism and manipulative amount-determining means, of a notched disk, an index compounded therewith and settable with the disk to varying positions measured by the number of items to be recorded or registered, means for moving said disk and index step-by-step, and a lock coöperating with the notched disk to automatically prevent manipulation of amount-determining means after said accounting mechanism has been operated the number of times predetermined by the setting of the index.

20 7. In a machine of the character described, the combination with accounting mechanism and manipulative amount-determining means, of a notched disk, an index compounded therewith and settable with the disk to varying positions measured by the number of items to be recorded or registered, means for moving said disk and index step-by-step, and a lock coöperating with the notched disk to automatically prevent manipulation of amount-determining means after said accounting mechanism has been operated the number of times predetermined by the setting of the index, said

25 lock comprising a lever to engage the notch of the disk, and a vibrating key - restorer adapted to be engaged by the lever.

8. In a machine of the character described, the combination with accounting mechanism and manipulative amount-determining means, of a notched disk, an index compounded therewith and settable with the disk to varying positions measured by the number of items to be recorded or registered, means for moving said disk and index step-by-step, and a lock coöperating with the notched disk to automatically prevent manipulation of amount-determining means after said accounting mechanism has been operated the number of times predetermined by the setting of the index.

30 9. In a machine of the character described, the combination with itemizing and totalizing mechanism, of an item counter adapted to be set forward varying numbers of steps, means for moving said counter backward step-by-step, and means coöperating with said counter to automatically prevent further operations of the itemizing mechanism after the counter has been carried all the way back, with provisions for restoring the counter to normal in an operation of the totalizing mechanism.

35 10. In a machine of the character described, the combination with itemizing and totalizing mechanism, of an item counter adapted to be set forward varying numbers of steps, means for moving said counter backward step-by-step against spring pressure, and means coöperating with said counter to automatically prevent further operations of the itemizing mechanism after the counter has been carried all the way back, with provisions for permitting spring restoration of the counter to normal in an operation of the totalizing mechanism.

40 11. In a machine of the character described, the combination with itemizing and totalizing mechanism, and manipulative amount-determining means, of an item counter adapted to be set forward varying numbers of steps, means for moving said counter backward step-by-step, and means coöperating with said counter to automatically lock the amount-determining means after operations of the itemizing mechanism to the number predetermined by the setting of the item counter, with provisions for restoring the counter to normal in an operation of the totalizing mechanism.

45 12. In a machine of the character described, the combination with itemizing and totalizing mechanism, and manipulative amount-determining means, of an item counter adapted to be set forward varying numbers of steps, means for moving said counter backward step-by-step against spring pressure, and means coöperating with said counter to automatically lock the amount-determining means after operation of the itemizing mechanism to the number predetermined by the setting of the item counter, with provisions for permitting spring restoration of the counter to normal in an operation of the totalizing mechanism.

50 13. In a machine of the character described, the combination with itemizing mechanism, of an item counter adapted to be set forward varying numbers of steps, means for moving said counter backward step-by-step against spring pressure, and means coöperating with said counter to automatically lock the amount-determining means after operation of the itemizing mechanism to the number predetermined by the setting of the item counter, with provisions for permitting spring restoration of the counter to normal in an operation of the totalizing mechanism.

55 14. In a machine of the character described, the combination with itemizing mechanism, of an item counter adapted to be set forward varying numbers of steps, means for moving said counter backward step-by-step against spring pressure, and means coöperating with said counter to automatically lock the amount-determining means after operation of the itemizing mechanism to the number predetermined by the setting of the item counter, with provisions for permitting spring restoration of the counter to normal in an operation of the totalizing mechanism.

- step-by-step against spring pressure, means for checking spring movement of the counter, means coöperating with the counter to automatically prevent further operations of 5 said itemizing mechanism after the counter has been carried all the way back, means for disabling the spring-checking means, and a stop to limit the spring movement of the counter.
- 10 14. In a machine of the character described, the combination with accounting mechanism and manipulative amount-determining means, of an item counter adapted to be set forward varying numbers of steps, 15 means for moving said counter backward step-by-step against spring pressure, means for checking spring movement of the counter, means coöperating with the counter to lock the amount determining means after 20 operations of said accounting mechanism to the number predetermined by the setting of the counter, means for disabling the spring-checking means, and a stop to limit the spring movement of the counter.
- 25 15. In a machine of the character described, the combination with itemizing and totalizing mechanism, of an item counter adapted to be set forward varying numbers of steps, means for moving said counter 30 backward step-by-step against spring pressure, means for checking spring movement of the counter, means coöperating with the counter to automatically prevent further operations of the itemizing mechanism after 35 the counter has been carried all the way back, means for disabling the spring-checking means, in an operation of the totalizing mechanism and a stop to limit the spring movement of the counter.
- 40 16. In a machine of the character described, the combination with itemizing and totalizing mechanism and manipulative amount-determining means, of an item counter adapted to be set forward varying 45 numbers of steps, means for moving said counter backward step-by-step against spring pressure, means for checking spring movement of the counter, means coöperating with the counter to lock the amount-deter- 50 mining means after operations of the itemizing mechanism to the number predetermined by the setting of the counter, means for disabling the spring-checking means in an operation of the totalizing mechanism 55 and a stop to limit the spring movement of the counter.
17. In a machine of the character described, the combination with itemizing mechanism, of a notched disk, an index com- 60 pounded therewith and settable with the disk to varying positions measured by the number of items to be recorded or registered, means for moving said disk and index step-by-step against spring pressure, means for 65 checking spring movement of the index and
- disk, a lock coöperating with the notched disk to automatically prevent further operations of said itemizing mechanism after reaching the number predetermined by the setting of the index, means for disabling the 70 spring-checking means, and a stop to limit the spring movement of the disk and index.
18. In a machine of the character described, the combination with accounting mechanism and manipulative amount deter- 75 mining means, of a notched disk, an index compounded therewith and settable with the disk to varying positions measured by the number of items to be recorded or registered, means for moving said disk and index 80 step-by-step against spring pressure, means for checking spring movement of the index and disk, a lock coöperating with the notched disk to automatically prevent manipulation of amount determining means 85 after said accounting mechanism has been operated the number of times predetermined by the setting of the index, means for disabling the spring-checking means and a stop to limit the spring movement of the 90 disk and index.
19. In a machine of the character described, the combination with itemizing and totalizing mechanism, of a notched disk, an index compounded therewith and settable 95 with the disk to varying positions measured by the number of items to be recorded or registered, means for moving said disk and index step-by-step against spring pressure, means for checking spring movement of the 100 index and disk, a lock coöperating with the notched disk to automatically prevent further operations of the itemizing mechanism after reaching the number predetermined by the setting of the index, means for dis- 105 abling the spring-checking means in an operation of the totalizing mechanism and a stop to limit the spring movement of the disk and index.
20. In a machine of the character de- 110 scribed, the combination with itemizing and totalizing mechanism, and manipulative amount-determining means, of a notched disk, an index compounded therewith and settable with the disk to varying positions 115 measured by the number of items to be recorded or registered, means for moving said disk and index step-by-step against spring pressure, means for checking spring move- 120 ment of the index and disk, a lock coöperating with the notched disk to automatically prevent manipulation of amount-determining means after the itemizing mechanism has been operated the number of times pre- 125 determined by the setting of the index, means for disabling the spring-checking means in an operation of the totalizing mechanism and a stop to limit the spring movement of the disk and index.
21. In a machine of the character de- 130

scribed, the combination with accounting mechanism and manipulative amount-determining means, of a notched disk, an index compounded therewith and settable with the 5 disk to varying positions measured by the number of items to be recorded or registered, means for moving said disk and index step-by-step against spring pressure, means for checking spring movement of the index and 10 disk, a lock coöperating with the notched disk to automatically prevent manipulation of amount-determining means after said accounting mechanism has been operated the 15 number of times predetermined by the setting of the index, said lock comprising a lever to engage the notch of the disk, and a vibrating key-restorer adapted to be engaged by the lever, means for disabling the spring-checking means, and a stop to limit 20 the spring movement of the disk and index.

22. In a machine of the character described, the combination with accounting mechanism and manipulative amount-determining means, of a notched disk, an index 25 compounded therewith and settable with the disk to varying positions measured by the number of items to be recorded or registered, means for moving said disk and index step-by-step against spring pressure, 30 means for checking spring movement of the index and disk, a lock coöperating with the notched disk to automatically prevent manipulative amount-determining means after said accounting mechanism has been operated 35 the number of times predetermined by the setting of the index, said lock comprising a notched lever to engage the notch of the disk, and a vibrating key-restorer having a projection to engage the notch of the 40 lever, means for disabling the spring-checking means and a stop to limit the spring movement of the disk and index.

23. In a machine of the character described, the combination with itemizing 45 mechanism, of a rotary item counter comprising members rotarily adjustable relative to each other, means applied to one of said members for turning it one step each time said itemizing mechanism operates, and 50 locking devices controlled by the other member of said item counter for preventing further operation of the itemizing mechanism when the number has been reached as predetermined by relative adjustment of the 55 two members.

24. In a machine of the character described, the combination with itemizing mechanism, of a rotary item counter comprising members clutched together but relatively 60 movable longitudinally and rotarily adjustable with relation to each other; means applied to one of said members for turning it one step each time said itemizing mechanism operates, and locking devices 65 controlled by the other member of said item

counter for preventing further operations of the itemizing mechanism when the number has been reached as predetermined by relative adjustment of the two members.

25. In a machine of the character described, 70 the combination with itemizing mechanism, of a rotary item counter comprising members rotarily adjustable relative to each other and bearing oppositely running count graduations, an index pointer associated with the graduations of one of said members, means applied to the latter for turning it one step each time said itemizing mechanism operates, and locking devices controlled by the other member of said item 75 counter for preventing further operations of the itemizing mechanism when the number has been reached as predetermined by relative adjustment of the two members.

26. In a machine of the character described, 80 the combination with itemizing mechanism, of a rotary item counter comprising members clutched together but relatively movable longitudinally and rotarily adjustable with relation to each other, said 85 members bearing oppositely running count graduations, an index pointer associated with the graduations on one of said members, means applied to the latter for turning it one step each time said itemizing 90 mechanism operates, and locking devices controlled by the other member of said item counter for preventing further operations of the itemizing mechanism when the number has been reached as pre-determined by 95 relative adjustment of the two members.

27. In a machine of the character described, 100 the combination with itemizing mechanism, of a rotatable item counter comprising members rotarily adjustable relative 105 to each other, a spring applied to one of said members, a stop limiting movement of the latter by said spring, means for turning said member step-by-step against the stress of said spring as one operation after another of the itemizing mechanism takes place, restraining means applied to said member to hold it in position as advanced by said turning means, locking devices controlled by the other member of the item 110 counter to automatically prevent further operations of the itemizing mechanism after the number has been reached as predetermined by relative rotary adjustment of the item counter members, and means for disabling the restraining means and the locking means at will.

28. In a machine of the character described, 115 the combination with itemizing and totalizing mechanism, of a rotatable item 120 counter comprising members rotarily adjustable relative to each other, a spring applied to one of said members, a stop limiting movement of the latter by said spring, means for turning said member step-by-step 125 130

- against the stress of said spring as one operation after another of the itemizing mechanism takes place restraining means applied to said member to hold it in position as advanced by said turning means, locking devices controlled by the other member of the item counter to automatically prevent further operations of the itemizing mechanism after the number has been reached as predetermined by relative rotary adjustment of the item counter members, and means for disabling the restraining means and the locking means when an operation of the totalizing mechanism is performed.
29. In a machine of the character described, the combination with itemizing mechanism and depressible amount-keys; of a rotatable item counter comprising members rotarily adjustable relative to each other, a spring applied to one of said members, a stop limiting movement of the latter by said spring, means for turning said member step-by-step against the stress of said spring as one operation after another of the itemizing mechanism takes place, restraining means applied to said member to hold it in position as advanced by said turning means, a notched disk compounded with the other member of the item counter, a vibrating key-restorer, a lever for locking the latter spring-pressed against the periphery of the notched disk, and means for disabling the spring-restraining means and said lever at will.
30. In a machine of the character described, the combination with itemizing and totalizing mechanism, depressible amount-keys; of a rotatable item counter comprising members rotarily adjustable relative to each other, a spring applied to one of said members, a stop limiting movement of the latter by said spring, means for turning said member step-by-step against the stress of said spring as one operation after another of the itemizing mechanism takes place, restraining means applied to said member to hold it in position as advanced by said turning means, a notched disk compounded with the other member of the item counter, a vibrating key-restorer, a lever for locking the latter spring-pressed against the periphery of the notched disk, and means for disabling the spring-restraining means and said lever when an operation of the totalizing mechanism is performed.
31. In a machine of the character described, the combination with accounting mechanism, depressible keys and total-setting devices; of an item counter comprising a pair of flanged disks clutched together for conjoint rotary movement, said disks bearing upon the peripheries of their flanges, reversely running count graduations and being separable by longitudinal movement to permit independent rotation of one of them; means for holding the disks permanently disengaged at will; a notched disk compounded with the independently rotatable flanged disk; a spring applied to the other flanged disk to resist its rotation; a stop to limit rotation thereof by the spring; a ratchet wheel geared to said last-named disk; a restraining pawl engaging said ratchet wheel; an actuating pawl adapted to engage the latter, means for reciprocating said actuating pawl in each operation of said accounting mechanism; a notched lever spring-drawn against the periphery of the notched disk; a vibratory key-restoring bail having a projection to occupy the notch of said lever; and operating connections between the total-setting devices and said lever and restraining pawl.
32. In a machine of the character described, including mechanism for enumerating items, comprising a key board and a main shaft, means whereby the function of the enumerating mechanism is temporarily interrupted after a predetermined number of items has been enumerated by locking the key board, and automatically restored by unlocking the key board at the next actuation of the main shaft.
33. In a machine of the character described, a main shaft, a counting disk, means for moving the same intermittently at each actuation of the main shaft, a key board, and means for locking the same after a predetermined number of such actuations.
34. In a machine of the character described, comprising a main shaft, a counting disk, means for moving the same intermittently at each actuation of the main shaft, a keyboard, means for locking the same after a predetermined number of such actuations and means for varying each number at the will of the operator.
35. In a machine of the character described, comprising a main shaft, a counting disk, means for moving the same intermittently at each actuation of the main shaft, a key board, means for locking the key board at each actuation of the main shaft and separate mechanism actuated from the counting disk whereby the unlocking function is interrupted.
36. In a machine of the character described, comprising a main shaft, a counting disk, means for moving the same intermittently at each actuation of the main shaft, a key board, means for locking and unlocking the key board at each actuation of the main shaft and separate mechanism actuated from the counting disk whereby the unlocking function is interrupted after a predetermined number of such actuations.
37. In a machine of the character described, comprising a main shaft, a counting disk, means for the moving of same intermittently at each actuation of the main shaft, a key board, means for locking and

unlocking the key board at each actuation of the main shaft and separate mechanism actuated from the counting disk whereby the unlocking function is interrupted, comprising a releaser moving with the counting disk and adapted to engage the key board locking means.

38. In a machine of the character described comprising a main shaft, a counting disk, means for moving the same intermittently at each actuation of the main shaft, a key board, means for locking and unlocking the key board at each actuation of the main shaft and separate mechanism actuated from the counting disk whereby the unlocking function is interrupted, comprising a releaser moving with the counting disk and adapted to engage the key board locking means, and means for moving the releaser relative to the disk.

39. In a machine of the character described, means adapted automatically to limit the items to be enumerated to a predetermined number, and after such number has been enumerated automatically to reset the limiting means to repeat the operation, in combination with the pointer and two scales, one of the scales serving to indicate the number of predetermined actuations to take place before resetting and the other serving to indicate the number of actuations which have taken place at any time when no resetting operation is to be effected.

40. In a machine of the character described, a main shaft including mechanism for enumerating items, means whereby the function of the enumerating mechanism is temporarily interrupted after a predetermined number of items has been enumerated, and automatically restored after the next actuation of the main shaft of the machine.

41. In a machine of the character described, the combination of accounting mechanism, actuating mechanism therefor, setting up devices, an item counter operated by said actuating mechanism, and means rendered effective by the item counter to disable the setting up devices after a predetermined number of operations of the actuating mechanism while leaving the latter free to further operate.

42. In an adding machine, a series of keys, a series of plates movable by operation of said keys, an element settable to prevent movement of said plates and thereby locking said keys, a device for setting and holding said element in position to prevent movement of said plates, connections for operating said device, and means indicating when said device is in position to hold said element to prevent movement of said plates.

43. In an adding machine, a series of depressible keys, a series of plates for locking said keys, an element movable to and from position to cause said plates to lock said keys, an adjustable actuator controlling said element, means for setting said actuator in position to actuate said element at a predetermined occasion, means indicating the position of said actuator, means for holding said actuator in its different positions, means for releasing said actuator, and means for restoring said actuator to its starting point.

44. In an adding machine, an item counting device comprising a support, a numeral scale on said support, a second numeral scale adjustable with respect to the first one, a latching device whereby said second numeral scale may be held in any desired adjustment with respect to the first-named scale, an actuator for holding said latching device in engagement, a signaling element, and means operated by said second numeral scale for causing said signaling element to signal.

45. In an adding machine, the combination of depressible keys operable to set up numbers, mechanism for recording numbers set up by said keys, a shaft controlling said recording mechanism, a device actuated by said shaft to indicate how many numbers have been recorded, settable devices operated by said indicating mechanism to prevent depression of said numeral keys, means for predetermining how many numbers may be recorded before said devices will be set to prevent depression of the keys, and means for disabling said devices at the will of the operator.
